The ornamental design for a privacy pod, as shown and described.

DESCRIPTION

FIG. 1 is a front perspective view of a privacy pod,
FIG. 2 is a front elevation view thereof,
FIG. 3 is a left end view thereof,
FIG. 4 is a top view thereof,
FIG. 5 is a bottom view thereof; and,
FIG. 6 is an enlarged detail view of the top, right, front corner.

The even length broken lines depict environment and form no part of the claim.

The dash-dot broken lines depict the locations and borders of detailed views and form no part of the claim.
